United States Patent Office.

LIBERTINE BULLARD, OF MARLBORO, MASSACHUSETTS.

Letters Patent No. 73,773, dated January 28, 1868.

IMPROVEMENT IN SHOES.

The Schedule referred to in these Letters Patent and making part of the same.

Be it known that I, LIBERTINE BULLARD, of Marlboro, in the county of Middlesex, and State of Massachusetts, have invented a new and useful Improvement in the Manufacture of Shoes, of which the following is a full, clear, and exact description, reference being had to the accompanying drawings, making a part of this specification, in which—

Figure 1 represents a shoe made on the plan of my improvement.

Figure 2 is a pattern of the counter.

Figures 3 and 5 are patterns of the vamp; and

Figure 4 is a pattern of the quarter.

The object of my invention is to provide for an economical use of the material employed in making up the shoe, and at the same time to secure a better-fitting and more serviceable shoe than those of the ordinary make; and the invention consists in so forming the parts that compose the shoe, and combining them together, as to give it the appearance of a boot over the foot, and insure a perfect fit to the heel and ankle.

Referring to the drawings, fig. 1 represents a shoe made of the several parts, which are cut, respectively, after the patterns shown. A is the vamp, cut in the form shown in fig. 3, of a single piece, and forms the instep and partly the sides of the shoe, and is sewed to the counter C in a vertical seam on either side, as shown in fig. 1. A', in fig. 5, represents another form of vamp, and is cut from one piece, and sewed only on one side, at α , the other side extending around to the centre of the heel in the rear, as at α' , and when in this form only one quarter, as shown at B, is required. B, fig. 4, represents the form of the quarter, of which two are used when the vamp is cut in the form shown in fig. 3. It is cut in the rear, so as to adapt the parts when sewed together to the contour of the heel. The quarter, B, is made to extend down to the sole of the heel at the rear of its junction α with the vamp, where it is properly secured. It is also sewed to the vamp on the curved line b , extending to the instep. The counter C is cut in the form shown in fig. 2, and when the pattern A of the vamp, fig. 3, is used, is sewed on both sides, as shown at α , fig. 1, to the said vamp, and extends around the heel on the outside of the quarter, by which means a smooth surface is secured on the inner sides of the shoe, thus obviating the difficulty often experienced in the turning down of the stiffening of the same.

The shoe thus made has the appearance of a boot at the sides, and the portions composing the shoe may be cut according to the quality of the leather required for each part, consequently saving much expense in working up the stock. The shoe may be finished when thus made up, in different styles, to suit the taste or fancy of the wearer.

What I claim as my invention, and desire to secure by Letters Patent, is—

The combination of the parts A or A', B and C, constituting, respectively, the vamp, quarter, and counter of a shoe, when the said parts are cut in the form and secured together in the manner shown and described.

In testimony whereof, I have signed my name to this specification in the presence of two subscribing witnesses.

LIBERTINE BULLARD.
